CLAIM

The ornamental design for a surgical console, as shown and described.

DESCRIPTION

FIG. 1 is a first perspective view of the surgical console of our new design;

FIG. 2 is a front elevation view of the surgical console of FIG. 1;

FIG. 3 is a right side elevation view of the surgical console of FIG. 1;

FIG. 4 is a left side elevation view of the surgical console of FIG. 1;

FIG. 5 is a top plan view of the surgical console of FIG. 1;

FIG. 6 is a rear elevation view of the surgical console of FIG. 1;

FIG. 7 is a bottom plan view of the surgical console of FIG. 1; and,

FIG. 8 is a second perspective view of the surgical console of FIG. 1.

The broken lines depict portions of the surgical console that form no part of the claimed design.

1 Claim, 8 Drawing Sheets
